Fig. 2.

UNITED STATES PATENT OFFICE

SAMUEL C. SHULTZ, OF CHILHOWEE, MISSOURI, ASSIGNOR OF ONE-HALF TO P. W. HOWARD, OF CHILHOWEE, MISSOURI

RURAL MAIL BOX STAND

Application filed November 8, 1928. Serial No. 317,993.

My invention relates to standards and more particularly to supports for rural mail boxes, the principal objects of the invention being to provide for removably positioning a mail box support adjacent the path of the mail carrier, for adjusting the elevation of the box, for rotating the box to suitably position the opening for convenient accessibility, and for latching the box in rotatably adjusted position.

In accomplishing these and other objects of the invention, I have provided improved details of structure, the preferred forms of which are illustrated in the accompanying drawings, wherein:

Fig. 1 is a perspective view of a mail box post and bracket constructed in accordance with my invention.

Fig. 2 is an enlarged elevational view partly in cross-section, on the line 2—2, Fig. 1, of the upper end of a supporting post and a box-supporting bracket mounted thereon.

Fig. 3 is a longitudinal sectional view of the upper end of a post-supporting frame on the line 3—3, Fig. 1, illustrating fragmentarily the post mounted therein.

Fig. 4 is an enlarged detailed perspective view of latching portions of the box-supporting bracket and bracket-supporting post.

Referring in detail to the drawings:

1 designates a supporting frame element comprising a head 2 having downwardly flaring side walls such as 3 and 4 providing tapering faces for attachment of legs 5, 6 and 7, preferably formed of angle irons, whereby the legs extend divergently for supporting the head.

The head preferably comprises a relatively thick body portion 8 having a vertical opening 9 to slidably receive a box-supporting post 10, and a rear flange 11 forming a recess 12 with the body portion. The legs 5 and 6 are mounted on the corners of the body portion with their flanges overlying adjacent walls and are secured to the head by a bolt 13 extending through a transverse opening 14 in the body portion. The leg 7 has a flattened upper end 15 secured to the rear flange 11 of the head by a bolt 16 having a head 17 mounted in the recess 12.

A set screw 18 mounted in the body portion of the head is adapted to engage the post to fix the post in vertically adjusted position.

Rotatably mounted on the upper end of the post is a mail box supporting bracket 19 comprising a relatively heavy preferably rectangular block 20 having a socket 21 adjacent one end to receive the upper end of the post, and angle irons 22 secured to the upper end of the block and extending laterally therefrom to provide a shelf-like structure to which the mail box may be secured. The shelf extends from the edge of the block adjacent the socket 21 so that the major portion of the block extends oppositely to the shelf from the socket for counter-balancing the box. The block 20 may rotate freely over the post, and I prefer to support the block on a radial flange or boss-like shoulder 23 located on the post in spaced relation with the end thereof and preferably integral with the post, whereby the block may rotate over the upper face of the shoulder.

I further provide a radial groove 24 in the upper face of the shoulder and a latching key or rib 25 on the lower face of the block 20 extending radially from the socket 21 to engage in the groove for latching the box-supporting bracket against rotation.

The legs have bent pointed portions 26 extending in the same direction and parallel with the axis of the frame, for perpendicular entrance into a horizontal ground surface.

Incidental improvements in structural detail may be provided such as ears 27 welded to the legs adjacent their bent portions to receive the foot of a person installing the device for pressing the points into the ground, and having openings 28 for receiving anchoring means such as stakes, which may be inserted in the openings and driven into the ground.

The device may be shipped in disassembled condition.

The legs may be conveniently and securely attached to the head of the frame by extending the bolt through the legs 5 and 6 and the body portion of the head, and by bolting the third leg to the flange of the head, whereby the legs are automatically spread and

their bent points adapted for vertical insertion into the ground. The post may then be inserted in the head member and adjusted to a height conforming to the contour of the ground for positioning the mail box suitably to the regulations of the Postal Department and the convenience of the carrier. The brackets may then be mounted on the upper end of the post and rotated to engage the rib in the latching groove so that the box will be positioned to receive the mail from the hand of the carrier.

The box may easily be released from engagement with the grooved shoulder of the post for rotation to facilitate inspection or to receive deposits from another direction, and preferably will be latched only in the one position.

It is apparent therefore that the box-supporting frame may be easily installed in a selected position, that it may be moved easily when grading or similar circumstances require temporary or permanent removal, and that in any location it may be adjusted to position the box at a suitable elevation.

The block 20 serves as a counterweight for retaining a substantial balance of the bracket and attached mail box to facilitate rotational movement of the bracket on its pivot.

30 What I claim and desire to secure by Letters Patent is:

1. In a device of the character described, a post-supporting frame including a head member, a pair of outwardly and forwardly diverging legs fixed to said head in a single plane, a third leg fixed to said head and diverging outwardly at a greater degree of inclination than said pair of legs, a box-supporting post mounted on said head member, and a lateral bracket on said post and projecting therefrom in a common direction with said forwardly diverging pair of legs.

2. In a device of the character described, a post-supporting frame including an elongated head member, a pair of outwardly and forwardly diverging legs fixed to said head adjacent one end, an outwardly diverging third leg fixed to the opposite end of the head, a box-supporting post mounted on said head member including an elongated block complementary to the head member, and a lateral bracket on said block and projecting therefrom in a common direction with said forwardly diverging pair of legs.

3. In a device of the character described, a post-supporting frame including an elongated head member, a pair of outwardly and forwardly diverging legs fixed to said head adjacent one end, an outwardly diverging third leg fixed to the opposite end of the head, a box-supporting post mounted on said head adjacent the pair of legs, an elongated block complementary to the head and supported on the post in offset relation, and a lateral bracket on said block projecting therefrom in a

common direction with said forwardly diverging pair of legs.

4. In a device of the character described, a post-supporting frame including an elongated head member having a vertical opening adjacent one end, a pair of outwardly and forwardly diverging legs fixed to said head adjacent the end having the opening, an outwardly diverging third leg fixed to the opposite end of the head, a box-supporting post rotatably mounted in said opening, an elongated block rotatably mounted in offset relation on the post and normally aligning with the head, and a lateral bracket on said block projecting therefrom in a direction opposite to the offset portion of the block.

In testimony whereof I affix my signature.

SAMUEL C. SHULTZ.
